UNITED STATES PATENT OFFICE.

CHARLES W. SPONSEL, OF WETHERSFIELD, CONNECTICUT, ASSIGNOR TO THE FAIRBANKS COMPANY, OF NEW YORK, N. Y., A CORPORATION OF NEW JERSEY.

ELEVATING-TRUCK.

1,367,926.

Specification of Letters Patent.

Patented Feb. 8, 1921.

Application filed March 10, 1920. Serial No. 364,659.

To all whom it may concern:

Be it known that I, CHARLES W. SPONSEL, citizen of the United States, residing at Wethersfield, in the county of Hartford and State of Connecticut, have invented a new and useful Improvement in Elevating-Trucks, of which the following is a specification.

This invention relates to those trucks which are designed to be rolled under platforms, racks, bins or containers on or in which are placed or piled machines, stock, merchandise or loads of other material, in shops, mills, freight houses, storerooms and manufacturing and mercantile establishments, and elevated for bodily lifting the load from the floor upon which it rests and transferring it to and depositing it at another locality without the necessity of directly handling or piling and repiling the articles, goods or material to be transferred.

The object of the invention is to provide a strong, durable, easily operated and relatively inexpensive apparatus of this nature which is so constructed that the elevator section of the truck will move vertically when raised for receiving and lifting a load and when lowered for depositing a load, thus permitting operation in a contracted space and allowing the load to be placed close to a wall or another load, also obviating the necessity of holding the truck fixed during the lifting and lowering operations, which elevator section is raised by a simple and powerful mechanism that is actuated in the same direction for lifting and for releasing the raised section and permitting it to lower under the weight of the load quietly and gently, obviating danger to the operator, and damage to the goods, truck and floor, and which is so designed that when the elevator is sustaining a load the actuating parts are on center or in such relation that they are locked, thus relieving the elevating mechanism from excess strain and eliminating all danger of the load accidentally dropping while being transferred from place to place, which transferring is accomplished through the elevating handle that is readily disconnected without unlocking the elevating mechanism when it is necessary to use it for drawing the load from one locality to another.

Figure 1 of the accompanying drawing shows a plan of a truck which embodies the

invention. Fig. 2 shows a central longitudinal section of the truck, with the parts in the positions occupied when the elevator section is raised. Fig. 3 is a similar view, with the elevator section lowered. Fig. 4 is a view looking toward the front end of the truck. Fig. 5, on larger scale, shows in detail the elevator actuating mechanism. Fig. 6 is a diagrammatic view showing the movements of the members which connect the elevator with the body section.

The body frame of the truck comprises two longitudinally extending side plates 1, preferably steel or malleable iron, connected at the rear end by a rod 2 and at the front end by a triangular head 3 which is desirably cast to shape. At the rear end the body is supported by a pair of wheels 4 secured to an axle 5 which has its end held in bearing plates 6 that are secured to the side plates. At the front end there is a single supporting wheel 7 on an axle 8 with intervening anti-friction bearings 9. This axle is held at its ends in bearings in a downwardly extending yoke 10 which is fastened to a pivot stud 11 that extends up through the head. Anti-friction bearings 12 are arranged between the top of the yoke and the under side of the head and a collar 13 is fastened on the upper end of the pivot stud to retain it in place. Pivotaly mounted on the ends of a pin 14 which extends through the pivot stud and collar are the L-shaped plates 15 between which the lower end of the operating and drawing handle 16 is secured.

The elevator frame which is somewhat smaller than the body frame comprises two longitudinally extending plates 17, preferably steel or malleable iron, which are connected at their ends by rods 18. The elevator frame near each end is connected with the body frame by two similar jointed members. Each of these four members consists of two corresponding members 19 which embrace and are pivotally connected with or fulcrumed on the side plate of the body frame and two corresponding links 20 which embrace and are pivotally connected with the side plate of the elevator frame. The rod 21 that forms the pivotal connection between the link members and the elevator frame extends transversely across the elevator frame so as to join the link members on the opposite sides. The lower ends of the members 19 are hinged to the link members.

by a rod 22 which extends across beneath the frames and connects the members 19 and links 20 on the opposite sides so that they will act together. On the outside of the outer piece of the link member that is pivoted to the elevator frame is a block 23 that fills the space between that piece and the inside of the body frame so as to keep the parts from twisting and binding. The hinged ends of the members 19 and links 20 on each side are connected by a link 24 that extends longitudinally in a plane directly below the side plate of the body frame. As the ends of the duplicated members 19 and 20 extend on both sides of the frame plates and as those on opposite sides and at both ends are connected together the structure may be built of light material and yet have the requisite strength to stand the heavy uses to which these trucks are put.

The members 19 turn freely on fixed points and serve to impart force or motion from a source of power, applied through the bars 24, to a source of resistance, the load on the links 20, or in other words, the members 19 swing on fulcrums and change the substantially horizontal pull of the bars 24 to a lifting or substantially vertical force on the links 20.

30 The cross rod 21 that pivotally connects the rear link members with the elevator frame, is connected with the cross rod 22 that extends across and hinges together the front link members, by a yielding connection or fluid check of common construction. This check has a cylinder 25 joined by a yoke 26 with the rod 22 and a piston rod 27 joined to the rod 21, the piston rod drawing outwardly from the cylinder freely and being retarded by the fluid pressure within when moving inward, in the well known manner of such checks. This permits the distance between the rear rod 21 and the front rod 22 to be increased without obstruction, but insures a slow and uniform shortening of the distance between these rods.

Secured to the under side of the head are a pair of blocks 28 which support a shaft 29. On the ends of this shaft crank arms 30 are fastened. The ends of these crank arms are joined by a pair of connecting rods 31 with the front cross rod 22. When the crank arms are in one extreme position the members 19 and 20 are in such relation that 55 the top of the elevator frame and the top of the body frame are in the same plane, Fig. 3, but when the crank arms are turned to the other extreme position the members 19 and 20 are turned in such manner as to lift 60 the elevator frame above the plane of the body frame, Fig. 2. The crank arms are so attached to the crank shaft that when the elevator frame is fully raised the center of the shaft is in a line between the center of 65 the rod 22 and the center of the pivotal con-

nection of the connecting rods with the cranks, or in other words, when the elevator frame is up the cranks are on center and the elevator frame cannot be lowered until the cranks are turned off from center. Attached 70 to the inside near the middle of each of the body frame plates is a vertical guide 32 and attached to the outside of each one of the elevator frame plates are guides 33, these guides co-operating to form a way which insures the vertical movement of the elevator frame when it is raised and lowered. 75

Keyed on the crank shaft is a ratchet 34, engaging with which are a stop pawl 35 and an actuating pawl 36, the latter pawl being 80 mounted on a pivot pin 37 between a pair of plates 38 loosely hung on the crank shaft. The ends of the pawl pivoting pin are extended beyond the plates and connected with the lower ends of a pair of curved 85 links 39. The upper ends of these links are joined by a rod 40 which is adapted to enter slots 41 in the projecting ends of the L-shaped handle plates 15. The ends of this rod are extended beyond the sides of the 90 handle plates so that they may be readily pushed out from the slots when it is desired to disengage the handle from the elevator actuating mechanism, for instance when the handle is to be used for drawing the truck. 95 The pawl plates have shoulders 42 adapted to engage with vertical surfaces 43 on the under side of the head for limiting the upward swing of the pawl, and they have surfaces 44 adapted to engage the horizontal 100 surfaces 45 for limiting the downward swing of the pawl.

When the handle of this truck is oscillated, through the curved links, pawl and ratchet, the cranks are given an intermittent 105 rotation and this through the connecting rods and links swings the lower ends of the jointed members 19 and 20 forward. This movement, as the elevator section cannot move forward, causes the elevator section to 110 rise vertically. With the cranks on center in front of the crank shaft the elevator frame is in its highest position, and when in this position the link members which are pivoted to it stand substantially vertical. 115 With the parts in these relations the elevator frame and any load it carries is suspended on the jointed members 19 and 20, those members of which that are pivoted to the elevator frame standing vertically and 120 those members which are pivoted to the body frame tending under the weight to swing backward, but being held from such movement by the connecting links and rods which are attached to the cranks. As this pull under these conditions is directly toward the crank shaft the elevator remains lifted 125 regardless of the weight placed upon it. When it is desired to lower the elevator frame one or more oscillations are given to 130

the handle, which through the pawl and ratchet rotates the cranks in the same direction as previously rotated until the cranks pass the center and then the weight of the load causes the elevator to descend, but this descent is easy for the reason that the movement is controlled by the fluid check. With or without a load on the truck the handle may be disconnected from the curved links by pushing the pin which connects the upper ends of the links from the slots in the ends of the handle plates and then the truck may be drawn by the handle and turned in any desired way. As the cranks are on center when the elevator is raised and is carrying a load, the locking of the parts does not depend upon the engagement of the handle plates with the links which oscillate the pawl. The simple mechanism described operates easily to lift heavy loads; it supports the loads firmly; is easily released; and lowers the loads gently.

The invention claimed is:—

1. An elevating truck comprising a body frame, wheels supporting said frame, an elevator frame, downwardly extending members with their upper ends fulcrumed to the body frame, downwardly extending links connecting the lower ends of said members with the elevator frame, said members and links supporting the elevator frame within the body frame, means extending longitudinally of and below the frames, connecting the lower ends of the members, and means for reciprocating said member connecting means.

2. An elevating truck comprising a body frame, wheels supporting said frame, an elevator frame, downwardly extending members with their upper ends fulcrumed to the body frame, downwardly extending links with their upper ends pivoted to the elevator frame, pivots connecting the lower ends of said members and links, and means connected with said pivotal connection between the members and links for oscillating the members and through the links raising and lowering the elevator frame.

3. An elevating truck comprising a body frame, wheels supporting said frame, an elevator frame, downwardly extending members with their upper ends fulcrumed to the body frame on both sides at each end, downwardly extending links with their upper ends pivotally connected to the elevator frame on both sides at each end and their lower ends pivotally connected to said members, said members and links supporting the elevator frame, means extending across below the frames and connecting the lower ends of the members and links, means extending lengthwise below the frames and connecting the lower ends of the members and links, and means for swinging back and forth said lengthwise connecting means.

4. An elevating truck comprising a body frame, wheels supporting said frame, an elevator frame, downwardly extending members with their upper ends fulcrumed to the body frame on both sides at each end, downwardly extending links with their upper ends pivoted to the elevator frame, transverse rods pivotally connecting the lower ends of said members and links on opposite sides at each end, longitudinal rods on both sides and connecting said pivot rods at each end, and means for reciprocating said longitudinal connecting rods and oscillating all the members and links together for raising and lowering the elevator frame.

5. An elevating truck comprising a body frame, wheels supporting said frame, an elevator frame, downwardly extending members with their upper ends fulcrumed to the body frame on both sides at each end, downwardly extending links with their upper ends pivotally connected to the elevator frame on both sides at each end, means below the frames connecting all of said members and links, and means connected with said connecting means below the frames for oscillating all of said members and links coincidently.

6. An elevating truck comprising a body frame, wheels supporting said frame, an elevator frame, downwardly extending members with their upper ends fulcrumed to the body frame on both sides at each end, downwardly extending links with their upper ends pivotally connected to the elevator frame on both sides at each end and their lower ends pivotally connected to said members, said levers and links supporting the elevator frame, means extending across below the frames and connecting the lower ends of the members and links, means extending lengthwise below the frames and connecting the lower ends of the members and links, means for swinging back and forth said lengthwise connecting means, and means extending between the lower ends of the links at one end and upper ends of the links at the other end of the frames for retarding the downward movement of the elevator frame.

7. An elevating truck comprising a body frame, wheels supporting said frame, an elevator frame, downwardly extending members with their upper ends fulcrumed to the body frame on both sides at each end, downwardly extending links with their upper ends pivotally connected to the elevator frame on both sides at each end and their lower ends pivotally connected to said members, said members and links supporting the elevator frame, means extending across below the frames and connecting the lower ends of the members and links, means extending lengthwise below the frames and connecting the lower ends of the members and links, means extending lengthwise below the frames and connecting the lower ends of the members.

and links, means for swinging back and forth said lengthwise connecting means, and a fluid check connecting the lower ends of the links at one end with the upper ends of 5 the links at the other end.

8. An elevating truck comprising a body frame, wheels supporting said frame, an elevator frame, downwardly extending members with their upper ends fulcrumed to the 10 body frame, downwardly extending links connecting the lower ends of said members with the elevator frame, said members and links supporting the elevator frame within the body frame, bars extending longitudinally below the frames and connecting the 15 lower ends of the members, cranks connected with said bars, a ratchet and pawl for revolving said cranks, and a handle for oscillating said pawl.

20 9. An elevating truck comprising a body frame, wheels supporting said frame, an elevator frame, downwardly extending members with their upper ends fulcrumed to the body frame, downwardly extending links 25 with their upper ends pivoted to the elevator

frame, pivots connecting the lower ends of said members and links, bars connecting the lower ends of the members, cranks connected with said bars, a ratchet and pawl for revolving said cranks, links for oscillating 30 said pawl, a handle for drawing the truck, and means for connecting said handle and links.

10. An elevating truck comprising a head, a body frame attached to said head, wheels 35 supporting said head and frame, an elevator frame within the body frame, downwardly extending members with their upper ends fulcrumed to the body frame on both sides at each end, downwardly extending links 40 with their upper ends pivotally connected to the elevator frame on both sides at each end, means below the frames connecting all of said members and links, a ratchet mounted in the under side of the head, a pawl for rotating the ratchet, links supporting said pawl, a swiveled draft handle, and links connected with the pawl supporting links and adapted to be engaged by the draft handle. 45

CHARLES W. SPONSEL.
